UNITED STATES PATENT OFFICE.

HAROLD G. GOULD AND KYLE DIRIAS OBENSHAIN, OF MCKINNEY, TEXAS.

SURGICAL APPLIANCE.

Application filed April 6, 1926. Serial No. 100,131.

This invention relates to surgical appliances for placing ligatures on blood vessels.

It is common practice in surgery to grasp the bleeding points with a pair of artery forceps, pass a ligature around the grasped tissues, and then tie said ligature with a surgeon's knot. This operation requires the use of both hands of the surgeon and frequently 10 an assistant is necessary to aid in holding the artery forceps.

An object of the present invention is the provision of a device for not only holding the tissues of a wound, but for tying a ligature on the bleeding tissues, the operation 15 being performed with one hand.

A further object of the invention is the provision of a device for holding tissues and tying a ligature about said tissues and 20 in which a conically shaped hollow barrel is mounted for sliding movement against the tension of a spring, said spring being adapted to operate the barrel for forcing a pair of jaws into clamping relation with tissue, 25 while a pair of knot carriers are employed in conjunction with a second spring that draws the knots tight when the loop of ligature is forced off the end of the conical barrel and placed around the tissues, a knife 30 being employed to sever the ligature when the operation is complete.

This invention will be best understood from a consideration of the following detailed description, in view of the accompanying drawings forming a part of the specification; nevertheless it is to be understood that the invention is not confined to the disclosure, being susceptible of such changes and modifications which shall define 40 no material departure from the salient features of the invention as expressed in the appended claims.

In the drawings:

Figure 1 is a longitudinal side view of a 45 device constructed in accordance with the principles of my invention.

Figure 2 is a longitudinal vertical section of the same.

Figure 3 is a plan view.

Figure 4 is a plan view of the device show-

ing the ligature in operative position on the tying device.

Figure 5 is a plan view showing the device in operation when the knotted loop has been forced off of the tying device. 55

Figure 6 shows a plan view of the device in operative position after the second knot has been forced up taut.

Figure 7 shows the position of the device after the ligature has been severed and the 60 knot tied.

Figure 8 is a fragmentary view in perspective of the knot tying device with a ligature in position to be tied.

Figure 9 shows a longitudinal view of a 65 modified form of the invention.

Figure 10 is a view in perspective of the same.

Figure 11 is a perspective view of the shears used in conjunction with the device 70 for cutting the ligatures after the knot has been tied.

Figure 12 is an end view of the device shown in Fig. 9.

Referring more particularly to the drawings, 10 designates a handle to which is secured at right angles a rod 11 having a reduced portion 12 which is embraced by a coil spring 13. One end of the coil spring abuts a shoulder 14 on the rod 11 while the 80 other end abuts a shoulder 15 on a barrel 16 slidably mounted on the rod 11. 75

The spring 13 is compressed by drawing the barrel 16 rearwardly and towards the handle 10 by means of the finger piece 17 secured to the barrel. A trigger 18 pivoted at 19 on the finger piece 17 has a pin 20 normally engaging a recess 21 in the rod 11 for retaining the barrel in a predetermined position as will be presently explained. A 90 spring 22 secured at one end to the finger piece presses against the trigger so that the pin 20 will be maintained in a perforation 23 in the sleeve 16 and against the rod 11 in order that the pin may drop into the 95 recess 21 when the pin alines with said recess.

The sleeve 16 has a conically shaped end 24 which normally receives the tying loop 25 of a ligature 26. The outer free end of the 100

rod 11 has a pair of resilient clamping jaws 27 secured at 28 to the rod. These jaws are adapted to expand and spread apart when the sleeve 16 is moved towards the handle 10 and the jaws are projected from the conical end 24 of the sleeve.

A device for tying the first knot 29 of the ligature is slidably mounted on the sleeve 16 and comprises a flat rod 30 provided with 10 lugs 31 and 32 forming a fork or U-shaped member at the free and forward end of the bar. The rear end of the bar has a depending arm 33 to which is connected a finger ring 34. The lugs 31 and 32 have slots 35 15 adapted to receive the strands of the ligature which are located between the knots 29 and 36. The rod 30 is guided on the sleeve 16 by means of spaced lugs 37 depending from a spring casing 38. The lugs embrace opposite side edges of the sliding rod 30 and a 20 sliding rod 39.

The sliding rod 39 carries the second knot tying device which consists of a pair of lugs 40 and 41. At the ends of said lugs are 25 provided upstanding ears 42 having passages 43 to receive the strands of the ligature. The strands are threaded into the passages 43 through transverse slots 44 which extend through the tops of the ears 42 30 and into the passages 43. The other end of rod 39 extends to the rear of the sleeve 16 and beyond the arm 33 and spring casing 38 and is provided with a depending arm 45 having a finger ring 46.

35 A coil spring 47 is located in the casing 38 and has one end connected to a rod 48 equipped with a button or clamp 49 to which is adapted to be secured the free ends of the ligature 26. The rod 48 is slidable in a passage at the front end of the casing 38. The rear end of casing has a passage through 40 which is mounted a tensioning bar 50 provided with teeth 51 adapted to engage the edge of the material of the casing surrounding the opening through which the bar is passed. A finger piece 52 on the end of the bar 50 is used for actuating said bar to tension the spring 47 and likewise the ligature 26. The casing 38 is secured to the sleeve 16 45 by means of straps 53.

The arm 33 has a lateral extension 33^a while arm 45 has a lateral extension 45^a whereby said arms will be sufficiently projected from the side of the barrel or sleeve 55 16 so that the finger pieces carried by said arms may be readily engaged by the fingers of the operator and whereby the arm 46 may easily clear the handle 10 when the barrel is moved rearwardly into engagement 60 with said handle.

In the modified form shown in Figures 9 to 12 inclusive the sleeve or barrel 16^a has a conically shaped portion 24 and the jaws 27 are slidably mounted within the barrel and 65 operated in a manner similar to the con-

struction shown in Figures 1 to 8 inclusive. The difference in the two devices consists in the lower semi-cylindrical slidably mounted member or bar 60 which has lugs 61 at its end provided with slots 62 through which is 70 threaded the ligature 63. This ligature has two knots 64 and 65.

A second member or bar 66 which is semi-cylindrical in shape is slidably mounted on the barrel above the member 60 and has slots 75 67 through which the ends of the ligature are inserted and slots 68 cut through the side of the barrel are provided to permit the ligatures passing from the slots 67 to the exterior of the member 66 so that the 80 ends may be connected to the button 49 as has been previously described. The bars or members 60 and 66 partially embrace opposite sides of the barrel 16^a.

A semi-cylindrical cutter 69 is slidably 85 mounted on the member 66 and is provided with a slot 70 through which projects a pin 71. The slot is inclined at an acute angle to a vertical plane passing through the axis of the barrel 16^a so that when the cutter 69 90 is moved outwardly by the finger piece 72 the cutter will be given a slight rotary motion over the member 66 so that when the knives 73 are moved across the slots 68 they will cut the ends of the ligature 63 in a 95 shearing action after the members 60 and 66 have been moved outwardly forcing the loop 74 off of the conically shaped portion 24 of the barrel 16^a and after the knots 64 and 65 100 have been tightened.

The operation of our device is as follows:

The loop 25 of the ligature is placed 105 around the conical end 24 of the barrel and held against slippage while threading by a spring 54 secured to the barrel. A single knot 29 is then formed and the strands of the ligature placed in the slots 35 of the lugs 31 and 32. A second loose knot 36 is then formed and the strands of the ligature are inserted through the transverse slots 43 110 into the passages 43 of the ears 42 on the ends of the lugs 40 and 41 of the second knot tying device. The free ends of the ligature are clamped or secured to the button 49. The bar 50 is then adjusted to place the 115 proper tension on the ligature through the spring 47. The device is now ready for use by a surgeon.

The handle 10 is now grasped and the trigger 18 is actuated to release the pin 20 120 from the recess 21 in the rod when a rearward pull is exerted on the finger piece 17. The barrel 16 is moved rearwardly on the rod 11 until the rear end of said barrel abuts the handle 10.

At this time, the resilient jaws 27 have 125 been forced outwardly from the front end of the barrel and because of their resiliency they will be forced apart and in open position. The jaws are then placed in embracing 130

relation with a tissue to be tied and the finger piece 17 is then released. The spring having been compressed forces the barrel 16 outwardly until a point is reached where 5 the pin 20 slips into the recess 21 when the barrel will be locked against further forward movement.

• The outer end of the barrel riding over the jaws 27 forces them together in clamping relation on the tissue. The outer ends 10 of the jaws at this time are substantially alined with the outer end of the barrel 16.

A finger of the operator is inserted through ring 34 and the ring and likewise 15 the bar 30 and lugs 31 and 32 are pushed forwardly. By reason of the spreading of said arms and the forward movement, the loop 25 is forced off the conical end 24 of the barrel 16 and the knot 29 is drawn up 20 tight upon the tissue. The bar 30 through the ring 34 is drawn rearwardly whence the strands of the ligature are released from the slots 36 of the lugs 31 and 32. The spring 25 47 maintains the ligature under tension during the first tying operation.

The second ring is engaged by a finger and moved forwardly, forcing the bar 39 along the barrel and lugs 40 and 41 to the end of the barrel, whereby the second knot 30 36 is drawn up tight on the first knot.

It will be appreciated that all the various elements of the device are so positioned and coordinated that they are adapted for operation by fingers of one hand of the surgeon 35 so that the other hand is free for other purposes.

We claim:

1. A surgical appliance for tying ligatures, comprising a barrel, means slidably 40 mounted in the barrel for clamping a tissue, means for holding a loose slip knot in embracing relation with the clamping means, means for removing the slip knot from the holding means and in embracing relation 45 with the tissue, and means for drawing the knot up tight on said tissue.

2. A surgical appliance for tying ligatures, comprising means for clamping a tissue, means for holding a loose slip knot 50 in embracing relation with the clamping means, means for removing the slip knot from the holding means and in embracing relation with the tissue, and means for drawing the knot up tight on said tissue, 55 and means associated with the removing means for cutting the ligature after the knot has been drawn tight.

3. A surgical appliance for tying ligatures, comprising a barrel, means slidably 60 mounted in the barrel for clamping a tissue, means for holding a plurality of loose slip knots in embracing relation with the clamping means, means for removing the slip knots from the holding means and in embracing relation with the tissue, and means

cooperating with the removing means for drawing the knots up tight on said tissue.

4. A surgical appliance for tying ligatures, comprising a hollow barrel, clamping jaws slidably mounted in the barrel, said 70 jaws adapted to be disposed normally within the barrel, said barrel adapted to carry a loop of the ligature having a loose knot, means on the barrel for forcing the loop of ligature off the barrel and for drawing the 75 knot up tight.

5. A surgical appliance for tying ligatures, comprising clamping jaws, a hollow barrel slidably mounted on the jaws, said 80 jaws adapted to be disposed normally within the barrel, said barrel adapted to carry a loop of the ligature having a plurality of loose knots, means on the barrel for forcing the loop of ligature off the barrel and for drawing the 85 knots up tight.

6. A surgical appliance for tying ligatures, comprising clamping jaws, a hollow barrel slidably mounted on the jaws, said 90 jaws adapted to be disposed normally within the barrel, said barrel adapted to carry a loop of the ligature having a plurality of loose knots, means on the barrel for forcing the loop of ligature off the barrel and for drawing the 95 knots up tight, a knife, and means for operating the knife to sever the ligature after the last knot has been drawn up tight.

7. A surgical appliance for tying ligatures, comprising a barrel, a clamping means operated by the barrel, said barrel being 100 adapted to hold a loosely knotted loop of the ligature, and knot tying means, said means consisting of a plurality of rods slidably mounted on the barrel and provided with lugs, said lugs having means for holding 105 the ligature.

8. A surgical appliance for tying ligatures, comprising a barrel, a clamping means operated by the barrel, said barrel being 110 adapted to hold a loosely knotted loop of the ligature, and knot tying means, said means consisting of a plurality of rods slidably mounted on the barrel and provided with lugs, said lugs having means for holding the ligature, tensioning means for 115 the ligature.

9. A surgical appliance for tying ligatures, comprising a barrel, a clamping means operated by the barrel, said barrel being 120 adapted to hold a loosely knotted loop of the ligature, and knot tying means, said means consisting of a plurality of rods slidably mounted on the barrel and provided with lugs, said lugs having means for holding the ligature, tensioning means for the ligature, 125 means for adjusting the tensioning means.

10. A surgical appliance for tying ligatures, comprising a barrel, a clamping means operated by the barrel, said barrel being 130 adapted to hold a loosely knotted loop of

- the ligature, and knot tying means, said means consisting of a plurality of rods slidably mounted on the barrel and provided with lugs, the lugs on one of the rods having slots to receive the strands of the ligature, said rod when operated forcing the loop off the barrel around a tissue adapted to be tied and causing the knot to be drawn taut.
11. A surgical appliance for tying ligatures, comprising a barrel, a clamping means operated by the barrel, said barrel being adapted to hold a loosely knotted loop of the ligature, and knot tying means, said means consisting of a plurality of rods slidably mounted on the barrel and provided with lugs, said lugs having means for holding the ligature, a spring for operating the barrel to actuate the clamping means.
12. A surgical appliance for tying ligatures, comprising a barrel, a clamping means operated by the barrel, said barrel being adapted to hold a loosely knotted loop of the ligature, and knot tying means, said means consisting of a plurality of rods slidably mounted on the barrel and provided with lugs, said lugs having means for holding the ligature, a spring for operating the barrel to actuate the clamping means, a tensioning means for the ligature on the barrel.
13. A surgical appliance for tying ligatures, comprising a handle, a rod secured to the handle, resilient clamping jaws on an end of the rod normally spread apart, a barrel slidable on the rod and having a conical end to receive a loosely knotted loop of the ligature, said barrel adapted to be moved into telescoping relation with the jaws for forcing said jaws into clamping action, a spring for operating the barrel to actuate the jaws, means for releasably retaining the barrel against the tension of the spring, and means on the barrel for forcing the loop of ligature off the barrel and for drawing the knot up tight.
14. A surgical appliance for tying ligatures, comprising a handle, a rod secured to the handle, resilient clamping jaws on an end of the rod normally spread apart, a barrel slidable on the rod and having a conical end to receive a loosely knotted loop of the ligature, said barrel adapted to be moved into telescoping relation with the jaws for forcing said jaws into clamping action, a spring for operating the barrel to actuate the jaws, means for releasably retaining the barrel against the tension of the spring, a rod slidable on the barrel, and a fork on the rod, means on the lugs for holding the ligature, said last named rod when operated forcing the loop of ligature off the barrel and drawing the knot up tight.
15. A surgical appliance for tying ligatures, comprising a handle, a rod secured to the handle, resilient clamping jaws on an end of the rod normally spread apart, a ligature having a plurality of loosely knotted loops, a barrel slidable on the rod and having a conical end to receive a loosely knotted loop of the ligature, said barrel adapted to be moved into telescoping relation with the jaws for forcing said jaws into clamping action, a spring for operating the barrel to actuate the jaws, means for releasably retaining the barrel against the tension of the spring, a plurality of rods slidable on the barrel, each of the rods having a fork adjacent the conical end of the barrel, means on the lugs for holding the ligature between the knotted portions of the loops of ligature, said rods adapted to be operated for successively forcing the loop off the end of the barrel and for drawing the knot up tight.
16. A surgical appliance for tying ligatures, comprising a hollow barrel, clamping jaws slidably mounted in the barrel, means for causing said jaws to move into clamping relation, a member partially embracing the barrel and slidably mounted on the barrel and having slotted lugs adapted to receive the ends of a ligature, a second member partially embracing the barrel and slidably mounted on the barrel and provided with slots to receive other portions of the ligature, said barrel having a conically shaped member adapted to receive a loop of the ligature, means for moving the barrel embracing members outwardly of the barrel for forcing the loop from said barrel.
17. A surgical appliance for tying ligatures, comprising a hollow barrel, clamping jaws slidably mounted in the barrel, means for causing said jaws to move into clamping relation, a member partially embracing the barrel and slidably mounted on the barrel and having slotted lugs adapted to receive the ends of a ligature, a second member partially embracing the barrel and slidably mounted on the barrel and provided with slots to receive other portions of the ligature, said barrel having a conically shaped member adapted to receive a loop of the ligature, means for moving the barrel embracing members outwardly of the barrel for forcing the loop from said barrel, a cutter slidably mounted on one of the barrel embracing members and provided with knives adapted to move over the ligature receiving slots for shearing the ends of the ligature.
18. A surgical appliance for tying ligatures, comprising a hollow barrel, clamping jaws slidably mounted in the barrel, means for causing said jaws to move into clamping relation, a member partially embracing the barrel and slidably mounted on the barrel and having slotted lugs adapted to receive the ends of a ligature, a second member partially embracing the barrel and slidably mounted on the barrel and provided with slots to receive other portions of the ligature,

said barrel having a conically shaped member adapted to receive a loop of the ligature, means for moving the barrel embracing members outwardly of the barrel for forcing the loop from said barrel, a cutter slidably mounted on one of the barrel embracing members and provided with knives adapted to move over the ligature receiving slots for shearing the ends of the ligature, and means for causing the cutter to have a slight rotary motion to produce a shearing action of the knives. 10
